G. O. LEHMANN,
VACUUM CLEANING AND DUSTING APPARATUS,
APPLICATION FILED MAY 18, 1922.

1,429,893.

Patented Sept. 19, 1922.

Inventor:
Gustav Oscar Lehmann
By *Kingsbury* atto

UNITED STATES PATENT OFFICE.

GUSTAV OSCAR LEHMANN, OF BERLIN, GERMANY.

VACUUM CLEANING AND DUSTING APPARATUS.

Application filed May 18, 1922. Serial No. 562,014.

To all whom it may concern:

Be it known that I, GUSTAV OSCAR LEHMANN, engineer, residing at Seestrasse 44, Berlin, N., Germany, have invented certain new and useful Improvements in Vacuum Cleaning and Dusting Apparatus (for which I have filed application in Germany, Feb. 21, 1921), of which the following is a specification.

10 Portable vacuum dusting and cleaning appliances are now largely used in preference to stationary appliances for the same purpose, which are expensive to manufacture and operate. In so far as such portable appliances are modelled on the usual type of stationary appliance, differing only in that apparatus can be carried or wheeled about, the saving effected is not great and the appliances are unwieldy. Moreover, they have 15 hitherto been found in practice to require considerable exertion for producing satisfactory results, needing both hands of an adult operator to manipulate them.

The object of my invention is to provide a 20 portable vacuum cleaner, comprising in a casing an electromotor, a fan, and a dust bag, having the following advantages:

1. Facility of manipulation, so that it can be handled by a child if desired.
2. Compactness, enabling it to operate under and behind chairs and like furniture.
3. Favorable distribution of weight.
4. Efficient suction, equal to that of stationary appliances.

35 To this end I fix the handle to the motor frame, and make it span an arc of about 90°, with one end fixed in line with the motor axis, or approximately so, and the other end abutting radially against the frame near the centre of gravity of the appliance. To 40 save weight, I use a light casing, which has no heavy portion of the apparatus to carry, but is itself carried by the motor frame, and tapers towards the nozzle.

45 An appliance embodying the invention is shown in the annexed drawings, in which

Fig. 1 is a longitudinal section of the same, and

50 Fig. 2 a cross section on the line II—II of Fig. 1.

The shaft of the electromotor 7 has bearings at 9 and 10 in a frame 8, which comprises a circular part 11 surrounding the motor and

supporting the same near the centre of gravity of the appliance. Upon the motor shaft 55 12 there is mounted a two stage fan 13, so that this fan is also supported by the frame 8. A handle 14, spanning an arc of about 90 degrees, has one of its ends, designated 15, fixed at 16 to the frame 8, in the longitudinal axis of the appliance. The other end of the handle, designated 17, abuts radially against the circular frame part 11, and is fixed to the same by means of rivets, bolts or the like 18 (Fig. 2). The handle, motor 60 and fan are thus combined to form a structure which supports the casing 19 of the appliance, which has a cap 20 at the end of a tapering part 21 enclosing the dust bag 22. As the casing 19, 21 has no heavy portions 70 of the apparatus to support, and more particularly no rotating, vibrating portions, it can be made of light and thin material, for example sheet aluminium. Thus a considerable saving of weight is effected, and the 75 centre of gravity is near the rear end, which is of considerable advantage in manipulating the appliance.

Various methods of joining the handle to the motor frame may be adopted, the important feature being that the handle is not, as heretofore, joined to a casing supporting the motor and fan, but is joined to the motor frame, which supports the casing.

The cap 20 is fixed by means of a coarse 85 screw thread or bayonet joint, and makes a tight joint around the mouth of the dust bag. It has an inwardly directed coned socket 22, adapted to receive the shank of the nozzle (not shown) or alternatively a 90 tube (not shown) having at its forward end a socket for the nozzle.

As the handle is near the centre of gravity the appliance can easily be manipulated with one hand, leaving the other hand free for 95 using a brush or shifting furniture or the like.

The motor is served in the usual way by means of a cable from a wall plug or lamp socket or the like, a switch being provided 100 on the handle.

I claim:

A portable vacuum dusting and cleaning apparatus comprising an electromotor, a fan, a dust bag, a casing and a handle for manipulating the appliance, characterized in that 105

the handle is fixed directly to the frame of the motor, spanning an arc of about 90 degrees, and having one end fixed to the frame approximately in line with the motor axis 5 radially near the centre of gravity of the appliance.

The foregoing specification signed at

Berlin, Germany, this 28th day of April, 1922.

GUSTAV OSCAR LEHMANN, ¹⁰

In presence of—
E. HOLLZERMER,
R. T. ANSPACE.

Certificate of Correction.

It is hereby certified that in Letters Patent No. 1,429,893, granted September 19, 1922, upon the application of Gustav Oscar Lehmann, of Berlin, Germany, for an improvement in "Vacuum Cleaning and Dusting Apparatus," an error appears in the printed specification requiring correction as follows: Page 2, line 4, after the word "axis" insert the words *and the other end abutting against the frame*: and that the said Letters Patent should be read with this correction therein that the same may conform to the record of the case in the Patent Office.

Signed and sealed this 31st day of October, A. D., 1922.
